UNITED STATES PATENT OFFICE

IRVING R. HIPPENMEYER, OF WAUKESHA, WISCONSIN, ASSIGNOR TO THE CREAMERY PACKAGE MFG. COMPANY, OF CHICAGO, ILLINOIS, A CORPORATION OF ILLINOIS

BOTTLE-WASHING MACHINE

Application filed November 10, 1928. Serial No. 318,319.

The invention relates to the bottle conveyor in bottle washing machines, and has for its principal object the provision of improved structure and arrangement of the bottle carrying pockets and their supports whereby increased capacity is attained for bottles being carried in like space and length of conveyor of former construction, with added strength and durability in the structure, ready 5 removability of individual pockets for replacement or repair, and simplicity of construction with low cost. Other objects and advantages will be apparent in the following detailed description of a preferred embodiment of the invention which I have illustrated 10 in the accompanying drawings.

15 In the drawings, Fig. 1 is a plan view of a portion of an assembled bottle conveyor. Fig. 2 is a side view in elevation of a portion of one cross row of pockets assembled in their support. Figs. 3 and 4 are sectional views taken on the planes of the lines 3 and 4 in Fig. 2.

20 Referring to the drawings, the reference numerals 1 and 2 indicate a pair of spaced conveyor belts, preferably of the link type, between which are supported successive cross rows of bottle holding pockets wherein bottles are conveyed through the washing machine and subjected to cleansing treatment by means well known in the bottle washing art.

25 Secured to successive opposite links in the two link belts 1 and 2 are L shaped brackets 3, each opposite pair of which rigidly supports a cross member 4. The member 4 is an integral channel shaped bar providing maximum rigidity within minimum lateral dimension, and is provided with a series of openings 5 in its web portion spaced longitudinally of the bar. Reinforcing cross members 6 may be secured at intervals between the legs or flanges of the channel bar.

30 Within each of the openings 5 is positioned a bottle receiving pocket 7, preferably of sheet metal structure formed suitably to

retain a bottle of standard shape known to the dairy industry. Each pocket 7 is provided with a plurality, preferably 4, of laterally extending ears 8 rigidly secured as by welding to the side wall of the pocket. The ears 8 of adjacent pockets are arranged to overlap in pairs and overlie the adjacent marginal portions of the cross member 4, being removably secured thereto as by bolts 9. Added rigidity and resistance to strain of the 35 mounting of the pockets in the channel bar is secured by striking inwardly from the flanges of the latter the tongues 10 on opposite sides of each pocket, the tongues 10 bearing against the walls of the pockets when the latter are 40 assembled in the cross bar support.

45 As will be apparent from Fig. 1, the arrangement herein disclosed enables the positioning of the successive rows of bottle pockets in the conveyor in close proximity, thus giving maximum bottle carrying capacity for a unit length of conveyor, and providing 50 staunch rigid support for the pockets and their contents.

55 I claim as my invention:

1. In a bottle washing machine, a bottle conveyor comprising a pair of spaced belts, a plurality of successively arranged cross members mounted on said belts, said cross members being channel shaped and provided with a series of openings in the web portion thereof, and a series of bottle pockets respectively secured in said openings, the flanges of said channel shaped cross members extending laterally adjacent the walls of said pockets and having portions thereof in abutment with said pocket walls.
2. In a bottle washing machine, a pair of spaced conveyor belts, a cross member end- 65 wardly supported upon said belts respectively and having a central web portion with marginal flanges extending longitudinally of said member, said web portion having a longitudinal series of openings, a series of bottle pockets positioned in said openings and 70

extending between said flanges, and a plurality of ears rigidly secured to each of said pockets and overlying said web portion, said ears being removably secured to said web portion, and a tongue rigidly extending from each of said flanges oppositely of the respective pockets into supporting abutment with said pockets.

In witness whereof I have hereunto attached my signature.

IRVING R. HIPPENMEYER.
